UNITED STATES PATENT OFFICE.

DAVID HINDAHL, OF CHICAGO, ILLINOIS, ASSIGNOR TO HARRY S. HART, OF CHICAGO, ILLINOIS.

DUMP CAR.

Application filed May 5, 1922. Serial No. 558,586.

To all whom it may concern:

Be it known that I, DAVID HINDAHL, a citizen of the United States, residing at Chicago, in the county of Cook and State of Illinois, have invented certain new and useful Improvements in Dump Cars, of which the following is a specification.

The present invention relates to dump cars.

An object of the present invention is to provide novel dump car construction whereby to increase the capacity thereof without increasing the overall dimensions and without sacrificing clearance.

A further object is to provide a construction of dump car which utilizes space now wasted in many types of dump car now in use.

Further objects will appear as the description proceeds.

Referring to drawings—

Figure 1 is a fragmentary longitudinal side elevation of a dump car embodying the present invention;

Figure 2 is a fragmentary top plan view of the construction shown in Figure 1; and

Figure 3 is a fragmentary end elevation and partial section of said car, the section being taken in a plane along the line 3—3 of Figure 1.

In recent years the importance of increasing the carrying capacity of railway cars has become recognized, this being especially true in connection with dump cars for carrying coal and other dumpable materials. In a certain well known type of dump car the floor at each end of the car over the trucks includes a long sloping member extending downwardly from the end of

the car near the top thereof toward the transverse center line of the car to form one wall of a transversely extending pocket or hopper, the center of the car being provided with a transverse A-shaped portion including transversely arranged dump doors. A hopper is arranged on each side of the center line of the car, each hopper having one of the dump doors referred to in one of its walls and one of the long sloping members

referred to as the other of its walls. In other words, the walls of said hoppers are formed by the transversely extending A-shaped portion in the middle of the car and the long sloping members at the ends of the car.

For the purpose of explaining the invention, a dump car has been illustrated having sides 10, ends 11 and a floor, the structure of which floor differs on opposite sides of the bolsters 12. The floor construction intermediate of the bolsters 12 includes a transversely arranged A-shaped portion, the upper part 13 of which is stationary and the lower part of which at each side of the A includes a transversely arranged dump door 14 pivoted about the transverse axis 15. This transversely arranged A-shaped portion, including the members 13 and doors 14, divides the car into two hoppers 16, only one of which is shown in the drawings. In the case of each of these transversely arranged hoppers 16, one wall is formed by the transversely arranged walls 13 and the door 14, the other transversely arranged wall being formed by the sloping member 17 which extends downwardly toward the transverse center line of the car, said sloping member in the car shown extending from a transverse line lying substantially over the bolster 12. The exit opening at the lower end of the member 17 is normally closed by the transversely arranged dump door 14, which when closed forms a tight seal with the lower edge of member 17. It will be understood that the dump doors 14 forming portions of the transverse central A-shaped structure swing inwardly toward each other when moved into open position and outwardly away from each other when moved into closed position. These transverse dump doors 14 may be operated by any preferred operating mechanism 18.

It will be understood that while I have here described a well-known form of hopper arrangement for dump cars this arrangement between the trucks forms no part of my present invention as other hopper and dumping arrangements may be substituted therefor. I have, however, shown a car in which the dumping mechanism between the trucks is generally at a lower level than the dumping mechanism over the trucks as will be described.

The floor portions over the trucks at each end of the car preferably take the form of hoppers 19, the lower portion of each of which is formed by a horizontally arranged door 20, which horizontally arranged doors 20 are mounted to swing about the longitu-

dinarily placed rods 21-21 which are supported from the center sill construction 22. The center sill construction 22 has the shedding frame members 23-23, which with the doors 20-20 form the bottoms of the hoppers 19-19, said doors extending substantially to the side edges of the car. The shedding frame members 23-23 are arranged in a sloping position extending downwardly from the longitudinal center line of the car toward the sides of said car. By thus having the doors 20 located below the top of the center sill structure, the carrying capacity of the car, and especially that of the end portions of the car, is greatly increased and at the same time the car is self-cleaning.

The exit flow of dumpable material in each half of the car is divided at the top of the sloping member 17, part of the material sliding longitudinally toward the transverse center line of the car and the remaining part flowing downwardly and sideways from the longitudinal center line of the car. Preferably the top of sloping member 17 will be above the center sill construction 22 and above the bottoms of hoppers 19-19. The car is entirely self-cleaning, whereby the labor of completely emptying the car is materially reduced.

One embodiment of the present invention has been described in detail. Many modifications will occur to those skilled in the art. It is intended in this patent to cover all such modifications that fall within the scope of the invention as defined by the appended claims.

I claim:

1. A dump car having sides, ends and a floor, the floor portions over the trucks of said car between the end of the car and the bolster being formed with a hopper on each side of the center sill, said floor portions comprising normally horizontal dumping members pivotally mounted along axes arranged longitudinally of said car adjacent to said center sill.

2. A dump car having sides, ends and a floor, a center sill structure rising into the floor above the trucks and forming shedding portions, said floor including normally horizontal dumping members cooperating with said shedding portions pivotally mounted about axes placed longitudinally of said car adjacent to said center sill structure.

3. A dump car having sides, ends and a floor, a center sill structure rising into the floor above the trucks and forming shedding portions, a transversely placed bolster, and a normally horizontal dump door pivotally mounted about an axis adjacent to said center sill structure placed longitudinally of the car lying between said bolster and the end of the car, said dump door being

cooperatively associated with said shedding portions to provide self-cleaning dumping means.

4. A dump car having sides, ends and a floor, the floor portions over the trucks having central downwardly and outwardly extending shedding portions, and normally horizontal dump means lying between the bolster and the end of the car and pivotally mounted on an axis lying longitudinally of the car adjacent to said shedding portions for dumping the load over the trucks downwardly and transversely with respect to the car.

5. A dump car having sides, ends and a floor, the floor portions over the trucks having central downwardly and outwardly sloping portions, and a normally horizontal dump door between the end of the car and the bolster, said dump door being pivotally mounted about an axis extending longitudinally of the car and adjacent to the center line of said car.

6. A dump car having sides, ends and a floor, the floor portion between the trucks comprising sloping portions providing a pair of hoppers spaced apart longitudinally of the car, the floor portion over the trucks and between the end of the car and the bolster being provided with normally horizontal doors on each side of the center sill, which doors are hinged along axes placed longitudinally of the car adjacent to the longitudinal center line of said car.

7. A dump car comprising a transversely placed A-shaped portion, sloping walls cooperating with the lower ends of said A-shaped portion to provide a pair of self-cleaning hoppers, transverse bolsters, said sloping walls terminating over said bolsters, the floor portions of said car between said bolsters and the ends of said car being formed to provide hoppers spaced on either side of the center sill, said hoppers including normally horizontal dump doors hinged along axes placed longitudinally of the car.

8. A dump car comprising a transversely placed A-shaped portion, sloping walls cooperating with the lower ends of said A-shaped portion to provide a pair of self-cleaning hoppers, a center sill, a pair of hoppers at each end of the car placed laterally of said center sill, said sloping walls terminating at a level above the bottoms of said last mentioned hoppers, said last mentioned hoppers including normally horizontal dump doors hinged along axes placed longitudinally of said car.

9. A dump car having sides, ends and a floor, the floor portion over the trucks and the floor portion between the trucks comprising load discharging means, the load discharging means between the trucks being at a lower level than the load discharging portion over the trucks, said load discharg-

ing portion over the trucks comprising hoppers on each side of the center sill and substantially horizontal hinged doors for discharging the load from said hoppers.

5 10. A dump car having sides, ends and floor, the floor portion over the trucks and the floor portion between the trucks comprising load discharging means, the load discharging means between the trucks being

at a lower level than the load discharging means over the trucks, the load discharging means over the trucks comprising stationary shedding portions over the center sill, and substantially horizontal hinged doors.

Signed at Chicago, Illinois this 1st day 15 of May, 1922.

DAVID HINDAHL.
